(57) **CLAIM**

I claim the ornamental design for a sleeve for packaging multiple plastic storage containers, as shown and described.

DESCRIPTION

FIG. 1 is a perspective view of the sleeve for packaging multiple plastic storage containers.

FIG. 2 is a front view of the sleeve for packaging multiple plastic storage containers; the rear view is a mirror image thereof.

FIG. 3 is a right-side view of the sleeve for packaging multiple plastic storage containers; the left-side view is a mirror image thereof.

FIG. 4 is a top plan view of the sleeve for packaging multiple plastic storage containers; and,

FIG. 5 is a bottom plan view of the sleeve for packaging multiple plastic storage containers.
